UNITED STATES PATENT OFFICE

163,742

CASING FOR AN ELECTRIC SAFETY LAMP

Fernand Louis Désiré Bogaerts, Jette, Belgium

Application March 31, 1950, Serial No. 8,901
In Switzerland October 3, 1949

Term of patent 14 years

(Cl. D48—24)

To all whom it may concern:

Be it known that I, Fernand Louis Désiré Bogaerts, a citizen of Belgium, residing at Jette, Belgium, have invented a new, original, and ornamental Design for a Casing for an Electric Safety Lamp, of which the following is a specification, reference being had to the accompanying drawing, forming a part hereof.

Figure 1 is a perspective view of a casing for an electric safety lamp showing my new design;

Figure 2 is a perspective view of the lamp taken from the opposite side from Figure 1, and

Figure 3 is a rear elevational view of the lamp casing.

I claim:

The ornamental design for a casing for an electric safety lamp, as shown.

FERNAND LOUIS DÉSIRÉ BOGAERTS.
